ESCUCHEON PLATE FOR A PULL

La Verne E. Clayton, Rockford, Ill., assignor to
Amerock Corporation, Rockford, Ill.

Original design application Aug. 12, 1970, Ser. No.
24,455, now Patent No. 222,233, dated Oct. 12,
1971. Divided and this application Mar. 25, 1971,
Ser. No. 128,224

Term of patent 14 years

Int. Cl. D8—06, 09

U.S. Cl. D8—179

FIG. 1

FIG. 2

FIG. 3

FIG. 4

FIG. 1 is a front view of an escutcheon plate for a pull showing my new design.

FIG. 2 is a side view as seen from the bottom of FIG. 1.

FIG. 3 is an end view as seen from the left of FIG. 1.

FIG. 4 is an enlarged fragmentary sectional view taken along the line 4—4 in FIG. 1.

This application is a division of my co-pending application Ser. No. D. 24,455, filed Aug. 12, 1970, now Pat. D. 222,233, Oct. 12, 1971.

I claim:

The ornamental design for an escutcheon plate for a pull, as shown.
